(No Model.)

J. PETERSON.

WHEELBARROW.

No. 363,168.

Patented May 17, 1887.

FIG. 1.

FIG. 2.

ATTEST,

John H. Redstone
Albert E. Redstone

INVENTOR,

John Peterson

UNITED STATES PATENT OFFICE.

JOHN PETERSON, OF SAN FRANCISCO, CALIFORNIA.

WHEELBARROW.

SPECIFICATION forming part of Letters Patent No. 363,168, dated May 17, 1887.

Application filed October 11, 1886. Serial No. 215,875. (No model.)

To all whom it may concern:

Be it known that I, JOHN PETERSON, a citizen of the United States, residing in the city and county of San Francisco and State of California, have invented a new and useful Wheelbarrow, of which the following is a specification.

My invention relates to improvements in wheelbarrows; and it consists in the construction of the parts.

It will be readily understood by reference to the accompanying drawings and the letters referring thereto.

Figure 1 is a side elevation; Fig. 2, an under plan view; Fig. 3, a broken view of the end of side rail in perspective; Fig. 4, a perspective view of the boxing or journal-bearing; Fig. 5, a perspective broken view of a side rail varied a little in form from that shown in Fig. 3. Fig. 6 shows the wheel in perspective.

A represents the tray of the wheelbarrow; B and B', the side rails of the wheelbarrow; C, the handles; D, the rim of the wheel; E, the arms or spokes of the wheel; F, the axle; G, the journals; H, the legs; I, the journal-box; J, the journal-bearing; K and K', the bolt-holes; L, the attaching slot; M, the recess in the end of the side rail to receive the journal-box.

The following is the construction of the same: I form the tray of suitable sheet metal in the form shown and attach them to the side rails by rivets in the usual way for such construction. I form the side rails from the T-iron or the beam-iron which are shown in Figs. 3 and 5. The handles are easily forged by simply bending down the flanges and hammering them round as far in upon the end as is required for a good hand-hold. For placing the boxing for the journals I cut out the mortise M from between

the flanges O and N or N and N and form the boxing I for the journal-bearings with a slot or mortise, J, to receive the connecting part or trunk. I then slip the journal-box in upon the trunk, between the flanges O N or N N, and bolt it fast through the bolt-holes K and K', which, in combination with the flanges O and N or N and N, hold the journal-box I firmly in place; and the wheel may be removed by unbolting and taking out the journal-boxes I.

The spokes E are made of flat iron and stand at an angle, so as to brace the wheel, as shown. There are eight of these spokes, and in order to employ the square iron for the axle, it is twisted in the center so as to turn the different ends of the axle one-eighth of a revolution, thus leaving a flat surface perpendicular to the point of attachment of the outer end of the spoke, and alternating, so that four of the spokes are attached to one half of the axle and four to the other part, so forming a strongly-braced and sufficiently-flexible wheel, which may be readily constructed from such material as is in common use and readily obtained.

Having thus described my invention, what I claim, and desire to secure by Letters Patent, is—

1. In metal wheelbarrows, the journal-box I, with attaching-slot L, bearing J, and bolt-hole K, in combination with the side rail, B, having the recess M and bolt-hole K', the flanges N and N or N and O, and handles C, constructed and operated substantially as and for the purposes set forth.

2. The twisted axle F and arms E, in combination with the rim D, constructed substantially as and for the purposes set forth.

JOHN PETERSON.
